UNITED STATES PATENT OFFICE.

ARTHUR OSBORNE, OF HYDE PARK, MASSACHUSETTS, ASSIGNEE TO
WILLIAM H. JACKSON, OF NEW YORK, N. Y.

DESIGN FOR A FACING FOR A FIRE-PLACE.

SPECIFICATION forming part of Design No. 14,402, dated November 6, 1883.

Application filed August 3, 1883. Term of patent 7 years.

To all whom it may concern:

Be it known that I, ARTHUR OSBORNE, a citizen of Great Britain, residing at Hyde Park, county of Norfolk, in the State of Massachusetts, have invented and produced a new and original Design for Facing or Frieze of a Fire-Place Casing, of which the following is a specification, reference being had to the accompanying drawing, forming part thereof.

10 The drawing represents a front elevation of my new design for the frieze of a fire-place casing.

The prominent characteristic feature of this new design consists of a medallion head with a hood-shaped helmet, and showing in profile the contour of a bearded face in high relief on a tablet occupying a central position on the frieze, and constitutes about one-third of the same. This central tablet, B, has a plane border, and presents a background representing curved waves. The right and left hand divisions of the frieze consist of panels with ornamental borders representing frames, excepting those portions which extend downward to the

25 lower edge of the frieze, which are intended to join a similarly-ornamented panel on a pi-

laster for the side of a fire-place. These two recessed panels A, A' exhibit only small interstices of plane background, being substantially covered with figures representing flowers with 30 open leaves and intertwining convoluted vines similar to the genus of plants known as the "convolvulus." Between the beaded moldings the ornamentation consists of transverse lines with terminating indentations next to the 35 molding, each of the rectangular corners with an open leaf.

Pilaster ornamentation of any desired figure may be used with my design for the frieze above described.

I claim—

The design for a facing or frieze for fire-places herein shown and described, the same consisting of the tablet B, with its medallion head, and the bordered floral panels A, A', 45 covered with vines and flowers similar to the convolvulus.

ARTHUR OSBORNE.
